SOAP DISH

Alban Sindler, Scotland Neck, N. C.

Application August 17, 1949, Serial No. 4,544

Term of patent 3½ years

(Cl. D4—3)

To all whom it may concern:

Be it known that I, Alban Sindler, a citizen of the United States of America, residing at Scotland Neck, in the county of Halifax and State of North Carolina, have invented a new, original, and ornamental Design for a Soap Dish, of which the following is a specification, reference being had to the accompanying drawing, forming a part thereof, wherein:

I claim:

The ornamental design for a soap dish, as shown.

ALBAN SINDLER.
